UNITED STATES PATENT OFFICE.

JAMES H. O'BRIEN, OF ST. LOUIS, MISSOURI.

LAMP-BURNER.

SPECIFICATION forming part of Letters Patent No. 603,116, dated April 26, 1898.

Application filed December 21, 1897. Serial No. 662,956. (No model.) Patented in England May 14, 1897, No. 11,985; in France May 18, 1897, No. 267,028; in Belgium June 16, 1897, No. 128,910, and in Austria October 6, 1897, No. 3,842.

To all whom it may concern:

Be it known that I, JAMES H. O'BRIEN, of the city of St. Louis, State of Missouri, have invented certain new and useful Improvements in Lamp-Burners, of which the following is a full, clear, and exact description, reference being had to the accompanying drawings, forming a part hereof.

This invention has been patented to me in the following foreign countries: Great Britain May 14, 1897, No. 11,985; France May 18, 1897, No. 267,028; Belgium June 16, 1897, No. 128,910, and Austria October 6, 1897, No. 3,842.

My invention relates to lamp-burners; and it consists in a novel construction, combination, and arrangement of the parts hereinafter shown, described, and claimed.

The object of my invention is to provide improved means whereby the upper corners of an ordinary lamp-wick may be raised or lowered independently of each other, as required to cause the flame of the lamp to burn evenly, even though the wick be not evenly trimmed.

Figure 1 is a transverse vertical sectional view taken through the center of a burner constructed in accordance with my invention. Fig. 2 is a horizontal sectional view taken approximately on the indicated line 2 2 of Fig. 3. Fig. 3 is a view in perspective of the wick-tube of my improved burner before said wick-tube has been positioned in said burner. Fig. 4 is a view in perspective of the wick-tube as it appears after being positioned in the burner. Fig. 5 is a transverse sectional view taken approximately on the indicated line 5 5 of Fig. 3. Fig. 6 is an enlarged vertical sectional view taken approximately on the indicated line 6 6 of Fig. 2.

In the construction of my improved burner the wick-tube 1 is a suitable length of flattened pipe, the same being vertically positioned in the lamp-burner in the usual manner. Formed in the lower portion of each side of the wick-tube is an aperture 2, which apertures are rectangular in form and located slightly above the lower edge of the wick-tube and at points slightly to one side of the center of said tube. Extending downwardly from the side edges of each of these apertures 2 are the slits 3 and 4, which slits 3 extend

entirely to the lower edge of the wick-tube, while the slits 4 stop a short distance from the lower edge. During the construction of these tubes the rectangular sections 5 between slits 3 and 4 and below the apertures 2 have their centers bent inwardly, and said sections are bent at right angles into the wick-tube. The positions these sections 5 assume after being so bent are clearly illustrated in Figs. 60 3 and 5. The pair of shafts 6 are mounted for rotation in the lower portion of the burner, and toothed wheels 7, such as are usually employed in lamp-burners, are fixed upon said shafts. Upon the outer end of each of the 65 shafts 6 is fixed a finger-wheel 8. After the burners have been provided with these shafts and toothed wheels the wick-tube 1 is passed downwardly into said burner, during which movement the toothed wheels 7 will pass into 70 the apertures 2 in said tube, and when so positioned said tube is soldered or fixed in any suitable manner. The sections 5 are now bent outwardly from the interior of the wick-tube or in such a position as that the lower 75 ends of said sections coincide with the sides of the wick-tube. The ordinary wick is now passed into the lower end of the wick-tube and upwardly therein until it can be engaged by the toothed wheels 7, and as said wick moves 80 vertically in said tube the sections 5 yieldingly engage the faces of said wick, and said sections may therefore be termed "friction-tongues." The toothed wheels 7 engage the wick on opposite sides and near the opposite 85 edges, and by manipulating one of said wheels 7 the corresponding upper corner of the wick may be raised or lowered independently of the other corner, and by manipulating both of said wheels simultaneously all parts of the 90 wick may be simultaneously raised or lowered. Each of the wheels 7, together with its corresponding friction-tongue, coacts to hold either side of the wick from vertical movement during the manipulation of the opposite toothed 95 wheel.

A lamp-burner of my improved construction is simple, inexpensive, easily constructed, and a very accurate adjustment for the wick is obtained, and the flame from said 100 wick can always be made to burn very evenly, even though said wick be unevenly trimmed.

I claim—

In a lamp-burner, a pair of shafts mounted in horizontal parallel positions, a wick-tube mounted between said shafts, a toothed wheel 5 upon one of said shafts and extending through a slot in one wall of said wick-tube near one of its edges and to the opposite wall of the wick-tube, a second toothed wheel upon the other one of said shafts extending through a slot in the opposite wall of the wick-tube near the opposite one of its edges and to the first-mentioned wall, said slots having each a long vertical slit 3 extending to the lower end of said wick-tube, and a shorter slit 4 extending 10 to a point adjacent said lower end, whereby the metal 5 between said slits may be bent 15 inwardly and permit the end of the said tube

to be slipped over the said toothed wheels and then said metal may be bent outwardly again after the tube has been placed in position, 20 and finger-wheels upon said shafts and upon opposite sides of the burner as required to raise and lower the corners of the wick independently of each other and as required to raise or lower the entire wick by manually 25 grasping one finger-wheel in each hand and exerting a twisting motion of the hands relative to each other, substantially as specified.

In testimony whereof I affix my signature in presence of two witnesses.

JAMES H. O'BRIEN.
